UNITED STATES PATENT OFFICE

DANIEL MAPES, OF MAMARONECK, NEW YORK, ASSIGNOR TO WALTER KIDDE & COMPANY, INC., OF NEW YORK, N. Y., A CORPORATION OF NEW YORK

RELEASE DEVICE

Application filed January 30, 1929. Serial No. 336,144.

This invention relates to devices for effecting the release of a fluid under pressure, such as carbon dioxide, for example, when conditions arise which render desirable the release of such fluid. In Letters Patent of the United States, No. 1,751,705, March 25, 1930, there is shown and described a device of this character in which the container in which the fluid is held under pressure is sealed against leakage by a seal, such as a rupturable disc, which is normally held in place against a seat provided for it by a support which is held normally against movement by restraining devices which can be released so as to permit the support to yield and the seal to be ruptured by the pressure against it. In the construction shown and described in that application the support is normally restrained from movement by toggles which are directly engaged by a fusible link which may part under the influence of a rise in temperature or may be pulled from engagement with the toggles.

In another application Serial No. 335,809 filed January 29, 1929, there is shown and described a device of the same general character in which the movement of the restraining toggle is prevented by a bent, two-part lever, which is held from movement through the engagement therewith of a flammable link, which can also be disengaged by a lever operated manually.

The present invention is particularly concerned with the means for effecting the release of the restraining lever which, through a toggle, prevents the yielding of the support for the seal. The releasing device, the operation of which is initiated manually or otherwise, is shown in the present case as arranged to cooperate with a two-part restraining lever such as that shown in the application last mentioned, but it will be understood that it is capable of being arranged for cooperation with a restraining lever other than that shown in the last named application and referred to herein. The invention will be described hereinafter with reference to the accompanying drawing in which:

Figure 1 is a view in sectional elevation of a release device which embodies the inven-

tion, a part of the protecting cap and a part of the container being also shown.

Figure 2 is a view of the release device in elevation as seen from the right hand in Figure 1, with the release pin in released position, the protecting cap being shown in section. 55

Figure 3 is a top view of the release device with the protecting cap in horizontal section.

Figure 4 is a detail view in side elevation of the toggles which cooperate with the support of the rupturable disc. 60

For convenience the same reference characters as those employed in both of said patent and application will be used herein as far as possible to indicate like parts. 65

In the embodiment of the invention illustrated a base or body *a*, suitably chambered, is formed at *a*¹ for connection to a container *k*. At *a*² it is formed with a seat to receive a rupturable disc *b* and is threaded internally to receive a bushing *c* by which the seal is pressed tightly against the seat *a*². The base or body is also threaded externally to receive a housing *d* which supports the devices to be described and has a connection, as at *d*¹, for the conduit through which the released fluid is to be conducted to the place of use. The seal *b* is supported against the internal pressure of the contents of the container by a support *e* which may take the form of a plunger with a free working fit within the bushing *c*. As shown the bore of the bushing is larger than the opening *a*³ between the container and the chamber of the bushing and the support *e* supports the seal *b* externally over an area such that the seal will not give away to the normal internal pressure in the container. The support has a bore *e*¹ considerably smaller than the outlet *a*⁴ and communicating, as at *e*², with the chamber of the housing *d* and the discharge outlet *d*¹. 70

The area of the seal thus left unsupported is relatively small so that the seal will not give way under normal internal pressure but will give way after the internal pressure rises above a predetermined degree. When, however, the support *e* is released and is free to move the seal will be ruptured by the internal pressure and the contents of the con- 75 80 85 90 95 100

tainer will be permitted thereby to escape in volume. All of the parts thus far described are arranged and operate substantially as described in both said patent and application.

5 As also described in the application Serial No. 335,809, filed January 29, 1929, the support *e* is normally restrained from movement by two toggles *f*, *f*¹, the toggle *f* bearing against the stem *e*³ of the support *e*, the 10 toggle *f*¹ bearing against an adjusting screw *f*⁴, and the two toggles bearing against each other at their heels, as at *f*⁵, in a point which is at one side of the line between the upper and lower bearing points of the two toggles, 15 pressure against the lower point of the toggle *f* tending to cause the toggles to swing further from such line. To prevent such movement of the toggles until the contents of the container are to be released pressure is applied to one of the toggles, such as the lower toggle, by a lever, which is preferably bent as shown and preferably consists of two parts *g*, *g*¹, pivotally connected as at *g*². The lever *g*, *g*¹ is pivoted to the housing *d*, as at *g*³, and 20 is arranged to bear normally against the toggle *f*, preferably through an adjusting screw *g*⁴. Obviously the lever *g*, *g*¹ operates practically as a single lever, but may be made in two parts, pivotally connected to each 25 other, as shown, to avoid danger of binding and also for convenience in manufacture and assembling. It will be observed that the point at which the toggle bears against the lever *g*, *g*¹, is outside of the vertical plane 30 which passes through the axis *g*³ on which the lever swings and the axis of pivot *g*², so that if the lever is not restrained it will yield to the pressure exerted through the toggle. 35

In the present instance no flammable or 40 fusible link is shown, the lever being restrained by a release pin *m* against which the end portion of the lever bears normally. The devices by which the release pin is withdrawn to release the lever *g*, *g*¹ will now be 45 described.

The release pin *m* is guided for vertical movement in a guide *m*¹ which is supported in the frame. The upper end of the release pin projects above the guide *m*¹ sufficiently to 50 engage the end of the lever *g*, *g*¹ and restrain it from movement. The release pin is held normally in locking position through the engagement of a lug or projection *m*² at its lower end with a spring latch *n* secured to 55 the housing and formed as shown in Figure 1, and having its lower end bent, as at *n*¹, under the lug or projection *m*² to hold the pin in its locking position. On the guide *m*¹ is 60 mounted a hammer *o* which is acted upon by a spring *o*¹, the hammer being formed, as at *o*², for contact with the spring *n* in the downward movement of the hammer to disengage it from the release pin and permit 65 the pin to descend under the influence of the

hammer when the part *o*², after releasing the spring *n*, strikes the lug or projection *m*².

The hammer *o* is held normally in its inoperative position with the spring *o*¹ under compression by a cable *p* which is held normally 70 under tension by any suitable device, such, for example, as a fusible or a flammable link or a manually operated latch. The cable is preferably passed down through the hammer and is coiled at its lower end below the hammer; as at *p*¹, when the hammer is in its elevated position to secure the necessary adjustment. 75

During shipment of the equipment the spring *o*¹ is extended, as shown in Figure 2, 80 but the release pin is held from movement by a safety pin *r* which is inserted through a hole *r*¹ in the lower end of the guide *m*¹ below the lower end of the release pin *m*. As a further safety feature the outlet connection *d*¹ is covered before installation by a cap *d*³ 85 and the cap is connected by a chain *d*⁴ with the safety pin *r* so that the cap cannot be removed until the device has been installed and the safety pin *r* has been withdrawn to place 90 the device in readiness for operation. 95

I claim as my invention:

1. In a device of the character described and including a container a movable means acting normally to prevent the release of fluid from the container, a toggle lever normally cooperating with said means to prevent movement thereof, a lever arranged to bear against the toggle lever to prevent movement thereof, a release pin normally engaging the second named lever to prevent movement thereof, and means to withdraw the pin to release the lever. 100

2. In a device of the character described and including a container a movable means acting normally to prevent the release of fluid from the container, a toggle lever normally cooperating with said means to prevent movement thereof, a lever arranged to bear against the toggle lever to prevent movement thereof, a release pin normally engaging the second named lever to prevent movement thereof, a latch normally preventing movement of the release pin, and means to disengage the latch. 110

3. In a device of the character described and including a container a movable means acting normally to prevent the release of fluid from the container, a toggle lever normally cooperating with said means to prevent movement thereof, a lever arranged to bear against the toggle lever to prevent movement thereof, a release pin normally engaging the second named lever to prevent movement thereof, a latch normally preventing movement of the release pin, a hammer to disengage the latch and move the release pin and thereby permit movement of the second named lever, and releasable means to retain the hammer normally in inoperative position. 125 130

4. In a device of the character described and including a container a movable means acting normally to prevent the release of fluid from the container, a toggle lever normally cooperating with said means to prevent movement thereof, a lever arranged to bear against the toggle lever to prevent movement thereof, a release pin normally engaging the second named lever to prevent movement thereof, a latch normally preventing movement of the release pin, a hammer to disengage the latch and move the release pin and thereby permit movement of the second named lever, releasable means to retain the hammer normally in inoperative position, and a safety pin to hold the release pin normally in inoperative position.

5. In a device of the character described and including a container a movable means acting normally to prevent the release of fluid from the container, a toggle lever normally cooperating with said means to prevent movement thereof, a lever arranged to bear against the toggle lever to prevent movement thereof, a release pin normally engaging the second named lever to prevent movement thereof, a latch normally preventing movement of the release pin, a hammer to disengage the latch and move the release pin and thereby permit movement of the second named lever, releasable means to retain the hammer normally in inoperative position, a safety pin to hold the release pin normally in inoperative position, a cap to cover the outlet, and a connection between the cap and the safety pin to prevent removal of the cap until the safety pin has been removed.

This specification signed this 15th day of January A. D. 1929.
